STRAND BRAKE

Isaac D. Houseman, Cleveland, Ohio

Application April 12, 1949, Serial No. 87,024

1 Claim. (Cl. 188—65.2)

1 This invention relates to a safety attachment for a workman when employed on a scaffolding or other support operatively disposed at the side of a wall or building structure; where such supporting equipment is used it has been the practice to provide a life line for the workman to manually grasp in the event the scaffold for any reason drops or is displaced. However, it is apparent that if an accident occurs without warning, especially if the workman is beyond the reach of the life line, he will be unable to grasp the latter. The safety attachment herein disclosed provides a connection between the workman and the life line, so that in the event of an accident, such as (a) the scaffold or support and/or its supporting means fall or break, (b) the scaffold or support is displaced (for example, due to the raising of some equipment), or (c) the workman loses his balance and falls off the scaffold the workman is automatically prevented from falling.

For purposes of illustrating the preferred application of the invention, the workman is shown standing on a scaffold, which may be raised and lowered by suitable block and tackle, associated with a life line attached to and depending from a high point of the wall or building structure and relative to which the scaffold may be adjusted from time to time upwardly or downwardly to change the working elevation, the safety attachment being detachably connected or clamped to the life line so as to be adjusted therealong when the scaffold is moved to a different level in either direction.

One object of the invention is to provide an improved safety attachment for a workman, having co-acting clamping elements for engaging the life line, one of the elements being movable and biased by a spring, whereby the attachment is adjustably connected to the life line, the workman being connected to the movable clamping element so that in the event of an accident the weight of his body operates through this element to effect a positive gripping of the life line by the clamping elements with sufficient pressure or grip to prevent the workman from falling.

In all safety attachments of the type referred to, of which I have knowledge, it has been the practice to adjustably clamp the attachment to the life line at an elevated position above the head of the workman, to permit the latter to freely move about the scaffolding without danger of engagement with the attachment. However, when lowering of the scaffolding becomes neces-

5 sary, release of the attachment from the life line for adjustment to a lower position could not be made without first raising the scaffolding, whereby the workman could effect the release and lowering of the attachment to a new position; thus, in addition to the labor expended and time lost in raising and lowering the scaffolding the workman was forced to hold the movable clamping element in its inoperative position, and 10 support the attachment while moving it downwardly to the lower position. Accordingly, another object of the invention is to provide an improved safety attachment of simplified construction and provided with means adapted to be operated by a workman on the scaffold for adjusting the attachment to a lower position, without raising the scaffolding or supporting the attachment during adjustment thereof.

Another object of the invention is to provide 15 an improved safety attachment embodying certain improvements in the form of construction shown in Letters Patent No. 2,458,943, dated January 11, 1949.

Other objects of the invention will be apparent to those skilled in the art to which my invention relates from the following description taken in connection with the accompanying drawing, wherein

20 Fig. 1 is a fragmentary perspective view of a building structure and a scaffold suspended in operative relation thereto, showing a workman on the scaffold, the workman being connected to the life line by an attachment embodying my invention.

25 Fig. 2 is a side elevation of the clamping mechanism mounted in adjusted position on the life line, parts being broken away.

30 Fig. 3 is an end elevation looking to the left of Fig. 2.

35 Fig. 4 is a top plan view.

30 In the drawing, 1 indicates as an entirety a portion of a building structure. 2 indicates as an entirety a scaffold adjustably suspended by the usual block-and-tackle 3 in operative relation to the structure 1. 4 indicates a safety or life line (preferably consisting of a rope) secured at its upper end to a high point of the structure or other elevated support and depending therefrom to a point adjacent or below the lowest position to which the scaffold may be lowered. The life line 4 is preferably disposed midway between the opposite ends of the scaffold 2 and may be related thereto on its inner or outer side.

45 The safety attachment consists of a belt 5 suitably bound around the workman's body, a clamp-

ing mechanism indicated as an entirety at 6 and a flexible connection 7 (such as a rope or chain) of any desired length detachably connected at its opposite ends to the belt 5 and mechanism 6, as later set forth. The belt 5 may be provided with suitable straps adapted to extend over the workman's shoulders to hold the belt in place; in the event the scaffold drops or the workman falls off therefrom and is suspended by the life line, as later set forth, the straps and belt together support the workman in suspended position without undue binding or pressure effect on his body, as would otherwise result if the belt 5 only were used. The clamping mechanism 6 consists of the following: 8 indicates an elongated rigid member, preferably of U-shape in cross section, so as to straddle the life line. In this arrangement, the mechanism 6 is guided endwise of the life line during adjustment thereof. The sides of the member 8, at their upper and lower ends, are extended laterally beyond the exposed side of the life line 4 to provide pairs of spaced arms 9, 10, respectively. 11 indicates a clamping element on the bottom wall of the member 8 spaced from its upper end and adapted to engage the life line as later set forth. The element 11 may consist of a section of metal welded to the bottom wall 8a of the member 8, as shown in the aforesaid Letters Patent, the exposed face of the metal section being concave and suitably knurled to insure a gripping relation with the life line 4; but by preference a portion of the bottom wall 8, endwise thereof, is embossed inwardly, substantially transversely, as shown at 8b, to provide the clamping element 11. 12 indicates a rocker of substantially bell-crank shape disposed between the arms 9 and fulcrumed on a removable pivot pin 13 extending through aligned openings formed in the outer end portions of the arms 9. The pin 13 is provided at one end with a head 13a between which and the adjacent arm 9 is provided a coiled spring 13b adapted to bias the pin 13 endwise (toward the left as viewed in Fig. 3). The opposite end of the pin 13 is formed with a diametrical slot 13x in which an abutment 13c is pivotally mounted intermediate its ends by a pin 13d supported in the side walls of the slot 13x. As shown in Figs. 3 and 4, when the abutment 13c is disposed at right angles to the pin 13, it engages the adjacent arm 9 to lock the pin 13 against endwise movement under the influence of the spring 13b, but when the abutment is in the position shown in dotted lines in Fig. 3, the pin 13 may be projected through openings in the arms 9 and opening in the rocker 12 or removed for a purpose later set forth. The outer end portion of the inner arm 12a of the rocker 12 provides a clamping element to co-operate with the clamping element 11 to engage the life line between them. The outer face of the arm 12a is substantially concave in cross section and knurled to insure adequate frictional contact with the life line 4. The other arm 12b of the rocker 12 is connected to one end of a spring 14. The opposite end of the spring is anchored to one of the arms 10. The spring 14 serves to rock the rocker 12 clockwise, as viewed in Fig. 2, and thus effect engagement of the clamping element 12a with the life line 4. As shown the arm 12b is relatively long as compared to the arm 12a to provide adequate leverage in operation and the spring 14 is of a size and strength to maintain the clamping element 12a against the life line and in opposition to the clamping element 11 under pressure to secure the mechanism 6 to the life line 4.

in any adjusted position thereof; that is, the frictional engagement of the clamping elements 11 and 12a with life line 4, under the influence of the spring 14, exceeds the tendency of the mechanism 6 due to its weight and that of the connection 7 to gravitate. By swinging or rocking the rocker 12 counter-clockwise, the clamping element 12a is disengaged from life line 4; when the life line 4 is disengaged in this manner, as later set forth, the mechanism 6 may be bodily adjusted endwise of the life line, such adjustment being effected as later set forth.

As shown, the outer end of the connection 7 is connected to the outer end of the rocker arm 12b, whereby the weight of the workman, in the event of an accident as hereinbefore set forth, exerts pull on the arm to insure a secure gripping of the life line by the clamping elements 11, 12a. The connection 7 is preferably detachably connected to the arm 12b by snap hook 15 and extends downwardly between the arms 10 and held therewithin by a pin 16 removably mounted in aligned openings formed in the outer ends thereof. The pin 16 is preferably similar in construction to the pin 13, whereby it may be positioned and removed in like manner. The arms 10 and pin 16 serve to maintain the outer end portion of the connection 7 in position to exert downward pull on the arm 12b substantially in its plane. 30 To reduce wear and friction on the connection 7, a roller 17 is rotatably mounted on the pin 16 between the arms 10. The flexible connection 7 preferably consists of an outer section 7a and an inner section 7b the adjoining ends of which are detachably connected together by snap hooks 18, 19, this arrangement serving to facilitate the connection of the workman to the arm 12b and his disconnection therefrom. The pins 13 and 16 are removable so that when initially hanging or connecting the mechanism 6 on the life line 4, the rocker 12, connection 7 and roller 17 may be disassembled to permit the life line to be positioned between the arms 9, 10 (as shown), whereupon these parts may be reassembled, thereby eliminating the trouble of reeving the life line in or through the pairs of arms 9, 10, and between the clamping elements 11, 12a.

20 indicates a linkage mounted on the member 8 and connected to the arm 12b of the rocker 12 for rocking the latter in opposition to the spring 14 to release the clamping elements 11, 12a, from the life line 4. In the form of linkage shown it consists of main link 20a pivotally mounted intermediate its ends on the outer face of one side of the member 8 below the arms 9 and a separate link 20b the inner end of which is pivotally connected by means of a bolt 21 to the outer end of the link 20a. The outer end of the link 20b is pivotally connected to the outer end of a bolt 22 extending laterally from the arm 12b. As the bolts 21, 22, are removable, either one may be removed to provide a disassembly of the linkage from the arm 12b when the mechanism is to be positioned on the life line or removed therefrom. The outer end of the link 20a is provided with a depending pull-cord 23 the lower end of which extends to a position within the reach of a workman on the scaffold 2 and is provided with a gripping device, such as a ring 23a for the workman to catch hold of.

When the scaffold is to be raised to a higher working level, it is first raised to a level thereabove so that the mechanism 6 may be repositioned. In adjusting the mechanism 6 upwardly the workman can grasp the link 20a or the pull-

cord 23 to release the clamping elements 11, 12a, from the life line, and when the mechanism is in the desired position, the link or pull-cord (as the case may be) is disengaged, whereby the spring effects operation of the rocker 12 to secure the mechanism 6 to the life line.

Operation.—When the mechanism 6 is initially connected to the life line, in its adjusted position, as above set forth, the workman may then don the belt 5 and attach the section 7b to the belt 5 and section 7a to insure his safety. In the event of an accident, such as herein referred to, it will be evident that the weight of the workman's body will exert a downward pull through the connection 7, and the latter will rock the rocker clockwise and cause an increased gripping effect by the clamping elements 11, 12a, on the life line 4, and hence prevent the workman from falling beyond a level limited by length of the connection 7 from the position of the mechanism 6.

When the scaffold 2 is to be lowered to a lower working level, the adjustment of the mechanism 6 to a lower position is effected by intermittent pulls on the pull-cord 23a the effect of which is to cause successive release and gripping movements of the clamping elements 11, 12a, with respect to the life line, the mechanism 6 serving to gravitate during the periods when the clamping elements are released or disengaged from the life line, the intermittent pulls or operations of the pull-cord 23a being continued until the mechanism 6 is adjusted at the desired position.

To those skilled in the art to which my invention relates many changes in construction and widely differing embodiments and applications of the invention will suggest themselves without departing from the spirit and scope thereof. My disclosures and the description herein are purely illustrative and are not intended to be in any sense limiting.

What I claim is:

A safety means for a workman, the combination with a scaffold adjustably suspended in relation to a wall for positioning at different working levels and a suspended life line disposed adjacent said scaffold, of a mechanism arranged to be adjustably clamped to said line above the scaffold in each adjusted position thereof, said mechanism consisting of an elongated member of U-shape in cross section enclosing said line, the sides of said member at its upper and lower

ends being extended laterally to provide aligned pairs of arms, a portion of the bottom wall of said member, remote from its upper end, being transversely embossed inwardly to provide on its inner face a clamping element, a lever fulcrumed on and between said upper pair of arms, a clamping element on the inner arm of said lever in opposed relation to said first mentioned clamping element and arranged to co-operate therewith to engage and disengage said life line, a spring connected at its opposite ends to the outer arm of said lever and one of said lower arms and arranged to rock said lever in a direction to effect engagement of said clamping elements with said life line under pressure, whereby said mechanism is adjustably fixed to and supported by the latter, a flexible member connected at its outer end to the outer arm of said lever and extending therefrom through said lower pair of arms and adapted to be connected at its outer end to the workman, so that the weight of the workman in falling serves to rock said lever and effect a rigid clamping engagement of said clamping elements with said life line, whereby the workman is held in a suspended position on said life line, a main link pivotally mounted intermediate its end on one of the sides of said elongated member, a separate link pivotally connected at its inner end to the inner end of said main link and pivotally connected at its outer end to the outer arm of said lever, and a pull-cord depending from the outer end of said main link and terminating at its lower end within reach of a workman on the scaffold, pull on said pull-cord serving to operate said lever in opposition to said spring to disengage said clamping elements from said life line to permit adjustment of said mechanism downwardly in relation to said scaffold.

ISAAC D. HOUSEMAN.
